US0D1020019S

(12) **United States Design Patent** (10) **Patent No.:** **US D1,020,019 S**
(45) **Date of Patent:** **** Mar. 26, 2024**

(54) **FLASHLIGHT**

(71) Applicant: **Shenzhen Jinba Technology Co., Ltd.**,
Guangdong (CN)

(72) Inventor: **Qidong Yang**, Guangdong (CN)

(73) Assignee: **Shenzhen Jinba Technology Co., Ltd.**,
Shenzhen (CN)

(**) Term: **15 Years**

(21) Appl. No.: **29/879,805**

(22) Filed: **Jul. 12, 2023**

(30) **Foreign Application Priority Data**

Jun. 15, 2023 (CN) 202330368433.2
